(57) **CLAIM**

The ornamental design for game football throwing target, as shown and described.

DESCRIPTION

FIG. 1 is an isometric view of a game football throwing target showing my new design;

FIG. 2 is a front elevational view thereof;

FIG. 3 is a top plan view thereof;

FIG. 4 is a bottom plan view thereof;

FIG. 5 is a right elevational view thereof;

FIG. 6 is a left side elevational view thereof;

FIG. 7 is a rear elevational view thereof; and,

FIG. 8 is an operational perspective view thereof showing my design in an environment of use.

The ring's net shown in FIG. 1–8, the goal and football player shown in broken lines in FIG. 8 depict environmental portions of the game football throwing target which form no part of the claimed design.
